ROTATABLE DISK NUMBER GAME DEVICE

Walter W. Marseille, San Francisco, Calif.

Application June 19, 1950, Serial No. 168,935

3 Claims.

(Cl. 273—1)

1

This invention relates to games and particularly to a device adapted to be used in a game of skill and chance.

It is an object of this invention to provide a game device that makes it possible for two or more players to play various entertaining and educative games, which may be played as games of chance in a hit-or-miss fashion or as games of skill based on an analysis of the possibilities of "moves" that the device offers.

Other objects and advantages of this invention will appear from the following specification taken in conjunction with the accompanying drawing in which:

Figure 1 illustrates a plan view of a device incorporating my invention;

Figure 2 represents a cross-sectional detail taken along the line 2—2 of Figure 1, with the device in "play" position;

Figure 3 illustrates a view taken along the line 3—3 of Figure 1, with the device in "home" position;

Figure 4 illustrates a cross-sectional view taken along the line 4—4 of Figure 2; and

Figure 5 represents a cross-sectional detail along the line 5—5 of Figure 3.

As indicated in Figure 1, the device consists of a plurality of rotatable members 10 which are provided about their peripheries with numerals, as indicated, or other indicia.

The rotatable members 10 are provided with centrally located bores and are rotatably mounted upon a spindle 11, as shown in Figures 2, 3, 4 and 5. As indicated in Figure 4, spindle 11 is provided with a predetermined number of longitudinal grooves 12, substantially as shown, which provide a plurality of tapered faces 13 and vertical faces 14. The rotatable members 10 are each provided with a recess 16 which houses a detent or pawl 17 and a spring 18. The springs 18 normally urge their associated detents radially inwardly as indicated so that the detents 17 act as pawls against the spindle 11 which, it will be recalled, is provided with longitudinal grooves 12. In effect, a ratchet is thus formed. As the member 10 is rotated in a clockwise direction, as illustrated in Figure 4, its pawl or detent 17 engages the sloping surfaces 13 with a camming action and continued rotation of the member 10 in a clockwise direction is permitted. However, counterclockwise rotation, as illustrated in Figure 4, is prevented by the engagement of the pawl or detent 17 with one of the surfaces 14.

The spindle 11 is provided with a plurality of

aligned orifices 19 each of which is positioned generally as illustrated in Figures 2, 3 and 4, for example, in the plane of the path of rotation of the pawls 17, whereby when a member 10 has been rotated to a predetermined point its detent or pawl 17 will be urged downwardly into one of the orifices 19 by the spring 18. When the pawl or detent 17 is so positioned within its cooperating orifice 19, that member 10 is locked against rotation in either a clockwise or counterclockwise direction as illustrated in Figures 4 and 5.

The spindle 11 is provided with a centrally aligned bore which forms a housing for a member 21 which, as illustrated in Figures 2, 3, 4 and 5, forms a support for a plurality of latches 22 and a reciprocating key 23. The latches 22 are mounted upon pins 24 for swinging movement about the axes of the pins 24 and are also provided with dogs 26 which are adapted to swing into or out of the orifices 19 in the member 11. The dogs 26 are of sufficient length that when they are urged to the position illustrated in Figure 2 they will force the detents 17 to a position whereby they are clear of engagement with the orifices 19. The key member 23 is adapted to be reciprocated longitudinally within the member 21 and is provided with a plurality of offset portions 27 generally as shown in Figures 2 and 3. When the key 23 is urged to the position illustrated in Figure 2, the offset portions 27 will engage the latches 22, urging the dogs 26 into the position illustrated generally in Figure 2, at which position the dogs 26 engage the detents 17, clearing the same from the orifices 19 thereby allowing the members 10 to be rotated in a clockwise direction. When the key 23 is reciprocated to the right, as illustrated in Figure 3, the offset portions 27 will no longer engage the latches 22 whereupon the dogs 26 will be removed from within the orifices 19, allowing the detents or pawls 17, assuming the same to be positioned over the orifices 19, to enter the orifices 19. If, however, a member 10 has been rotated to a point where its detent 17 is in a position remote from the orifice 19, the member 10 may be rotated in a clockwise direction, as viewed in Figure 4, and may continue to be rotated in that direction until its detent or pawl 17 again engages the hole or orifice 19.

The key 23 is normally urged to the position indicated in Figure 3 by the influence of the spring 28. However, the tension of the spring 28 may be overcome by an operator and key 23 may be urged to the left, as illustrated in Figure 2, tending to clear all of the detents 17

from their cooperating and respective orifices 19 whereby each of the members 10 is free to rotate in a counterclockwise direction as shown.

As indicated particularly in Figure 1, the outer peripheries of the members 10 are provided with indicia which in this case consist of numbers 1 to 9 to zero inclusive. The zero on each member 10 may in each instance be placed over the respective detent 17.

The spindle 11 is threaded at each end and is provided with hub caps 31 and 32 which prevent lateral movement of the members 10 and which retain the members 10 in the proper position with respect to the orifices 19.

Each of the hub caps 31 and 32 is provided with an indicia which, as illustrated in Figure 1, may consist of a painted dot 33 and the device is preferably manufactured and assembled in such a manner that when it is properly assembled the dots 33 upon the hub caps 31 and 32 will be in alignment with the orifices 19 in the spindle 11. In this event, and assuming that the indicia "zero" are immediately overlying their respective detents 17, it will be obvious that when all of the members 10 have been rotated to a position at which the figures "zero" are in alignment with the indicia 33 that all of the detents or pawls 17 will be positioned within their respective orifices 19 rendering rotation of the members 10 impossible. This may be termed "home" position. All other positions of the members 10 may be referred to as "play" positions. When it is desired that the members 10 be cleared or freed for rotation, the key 23 is moved to the left, as illustrated in Figure 1, by gentle pressure upon the protruding cap 34 whereby the offset portions 27 of the key 23 will engage the lower sides of the latches 22, urging the dogs 26 into the orifices 19 and forcing the detents 17 upwardly against the pressure of the springs 13 to a point at which the detents or pawls 17 clear the outer periphery of the spindle 11. As has previously been pointed out, the members 10 may then be rotated in a clockwise direction as indicated in Figure 4, but they may not be rotated in a counterclockwise direction as indicated in that figure for the reason that the detent 17 will then engage one of the radially upright surfaces 14.

Operation of the device may briefly be described as follows: Let it be assumed that the device is assembled as generally indicated in Figure 1, in such a manner that when the indicia "zero" are aligned with the indicia 33 on the end caps 31 and 32, all of the pawls or detents 17 associated with the rotatable member 10 are positioned within their respective orifices 19 in such a manner that the members 10 are in "home" position and are locked against rotation. Movement of the member 34 as described will urge the key 23 to the left as illustrated in Figure 2 whereby the offset portions 27 on the keys 23 will engage the latch members 22 and urge the dogs 26 into the orifices 19. As has previously been explained, when the dogs 26 are urged into the orifices 19, the detents 17 are urged upwardly against the tension of the springs 18 to a point at which they clear the outer periphery of the spindle 11. The members 10 are then free to be rotated to "play" position in a clockwise direction as has previously been described. As the members 10 are rotated in a clockwise direction, the detents 17 will engage the successive sloping surfaces 13 which will result in a camming action between the surfaces 13 and the

members 17 whereby the members 17 will ride over the surfaces 13 and be urged upwardly against the tension of spring 16, permitting the continued clockwise rotation of the members 10. However, upon a complete rotation of any one of the members 10 its detent 17 will engage its respective orifice 19 preventing further rotation, either clockwise or counterclockwise of the member 10. When all of the members 10 have been rotated one complete revolution from the previously described "home" position, all of the indicia "zero" will be aligned with the indicia 33 on the caps 31 and 32 and the members 10 will again be at "home" position.

This device may be utilized in connection with a game as follows:

After the device has been put in "play" position by pressing the member 34, as previously described, in such a manner that the rotatable members 10 may be rotated, two or more players take turns rotating the members 10. Each player rotates one member 10, and I contemplate that the rules of the game require that he move each member 10 at least one step. By "step" I refer to sufficient movement to bring the next succeeding indicia into line between the dots 33. However, the player may rotate the member 10 more than one step. When one player has completed the movement or play he desires, the device is passed to the second player who likewise selects one of the members 10 and rotates the same one or more steps. It will be understood that each of the members 10 will ultimately return to "home" position from which it may not be moved. The player moving the last member 10 to "home" position is declared winner. Those skilled in the art will recognize the above described game as being related to the Chinese number game of "Nim."

It is to be understood that I have illustrated but one manner of indicating "home" position, that is by locking each member 10 against further rotation. Other means of indicating "home" position may likewise be utilized, including, for example, some signal utilizing sound.

I claim:

1. In a device of the character described, a plurality of rotatable members mounted upon a spindle, pawls associated with said rotatable members which are adapted to engage longitudinal grooves in said spindle to permit rotation of said members about said spindle in one direction only, means comprising a plurality of aligned orifices in said spindle to prevent rotation of said members about said spindle in either direction when the same are engaged by said pawls, said spindle comprising a hollow tube, latch means within said spindle normally disengaged from said orifices and movable into and out of said orifices, said latch means adapted to engage said pawls and disengage the same from said orifices when said means are positioned within said orifices, and a reciprocating key adapted to actuate said latches.

2. In a device of the character described, a plurality of rotatable members mounted upon a spindle, each of said members having a plurality of indicia thereon, and at least one of said indicia being common to each of said members, pawls associated with each of said rotatable members adapted to engage longitudinal grooves in said spindle and to prevent rotation of said members about said spindle in one direction and to permit rotation of said members of said spindle in the

opposite direction, means in said spindle comprising a plurality of aligned orifices therein adapted to engage said pawls in a predetermined point to prevent rotation of said members in either direction, end pieces on said spindle, each of said end pieces being provided with an indicia identical to said common indicia, the orifices in said spindle being so aligned that when said pawls are positioned therein, all of said common indicia upon said rotatable members and said end members will be in alignment.

3. In a device of the character described, a plurality of rotatable members mounted upon a spindle, each of said members having a plurality of indicia thereon, and at least one of said indicia being common to each of said members, pawls associated with each of said rotatable members adapted to engage longitudinal grooves in said spindle and to prevent rotation of said members about said spindle in one direction and to permit rotation of said members of said spindle in the opposite direction, means in said spindle comprising a plurality of aligned orifices therein adapted to engage said pawls in a predetermined point to prevent rotation of said members in either direction, end pieces on said spindle, each

of said end pieces being provided with an indicia identical to said common indicia, the orifices in said spindle being so aligned that when said pawls are positioned therein, all of said common indicia upon said rotatable members and said end members will be in alignment, latch means in said spindle movable into and out of said orifices and adapted to engage said pawls and disengage the same from said orifices, and a reciprocating key adapted to actuate said latches and to determine their position with respect to said orifices and said pawls.
